STOKER FUEL DEFLECTOR

Andrew Bayreuther, Albany, N. Y., assignor to
The Standard Stoker Company, Incorporated,
a corporation of Delaware

Application June 13, 1930, Serial No. 460,835

9 Claims. (Cl. 110—101)

This invention relates to stokers and more particularly to improved means in a stoker for deflecting fuel.

It is an object of this invention to provide in a stoker, a deflector that is easily and readily adjustable and capable of deflecting fuel to any portion of the fuel bed.

It is a further object of this invention to provide a deflector mounted on a pivotal axis movable transversely, the deflector being arranged to move about said axis.

With these and other objects in view, which will become apparent as the description proceeds, the invention resides in the construction, combination and arrangement of parts, hereinafter more fully described and claimed, and illustrated in the accompanying drawings, in which

Fig. 1 is a partial vertical longitudinal section of the stoker and a portion of the locomotive with the invention in place;

Fig. 2 is a plan view of the structure shown in Fig. 1; and

Fig. 3 is a vertical section on the line 3—3 of Fig. 1.

25 In the figures, 10 designates a boiler firebox of conventional design having a backhead 11 with a firing opening 12, and provided with the grate 13. Fuel is delivered to the firebox by suitable stoker mechanism, only so much being shown as is necessary to a complete understanding of this invention.

The forward tubular conduit section or riser of a flexible conduit system extending from a source of fuel supply, as the bin of a locomotive tender, to the firing opening 12 of the boiler is designated as 14. The riser 14 is carried from the backhead 11 by a supporting bracket 15. The riser terminates at its lower end in a spherical seat 16 receiving the ball member 17 of a conduit section 18 leading forwardly from a source of fuel supply.

40 From its lower end the riser extends upwardly and forwardly, flaring outwardly at its upper end, and communicates with the firing opening 45 12 through its laterally spreading and substantially horizontal mouth portion 19. The mouth portion 19 is provided with the flanges 20, 20a for attachment to the backhead by suitable fastening means, as by bolts. This mouth portion 50 is formed with an upstanding wall 21 to which is detachably mounted a distributor plate 22, and forms an extended floor portion of the riser projecting through the firing opening 12 of the backhead. The riser 14 is provided with an opening 55 23 through which access may be had to the in-

terior thereof. A cover 24 is provided for the opening 23. This cover is hinged at its upper end at 24a to the riser 14 and is held in closed position by a latch 25. Rearwardly of the distributor plate 22 and outside of the firebox is a vertically disposed nozzle or distributor head 26 to which pressure fluid such as steam is supplied by a desired number of supply pipes 21. The nozzle 26 is provided with openings 28 in horizontal alignment for emitting a fan-shaped blast of fluid 10 across the distributor plate.

Disposed in the conduit section 18 is a screw 29, preferably formed with an additional flight 30 at its forward end to assist in insuring a continuous stream of fuel.

15 In stoking devices of the character described and illustrated in the drawings, it has been found in practice that the screw means has a tendency to discharge more fuel to one side of the riser than to the other and in turn the fuel stream delivered on to the steam blast is of unequal volume and more fuel is spread over one side of the firebox than the other, establishing troublesome fire conditions. The side to which more fuel is delivered depends upon the direction of rotation 20 of the screw means and whether it is a left or right hand screw.

25 This invention provides novel means to overcome this uneven delivery and distribution of fuel comprising the deflector member 31 provided with the vane 32 pivotally mounted in the upper portion of the riser 14 and arranged to be movable transversely of the riser 14 as hereinafter described. The upper portion of the riser cover 24 is provided with a rectangular 30 slot or opening 33 forming a guide for the transverse movement of the deflector 31. The deflector vane 32 depends in a perpendicular position from its shaft portion 34. The shaft 34 extends up through the rectangular opening 33, 35 a handle 35 being securely fastened to the top of said shaft and arranged to give movement to the deflector vane 32 to any desired degree of deflection about its shaft 34 as an axis. The angular adjustment or the degree of deflection of 40 the deflector about the shaft 34 is regulated independently of the transverse movement of the deflector in the riser by moving the handle 35 to the right or left. The deflector may therefore, be given an angular adjustment from any one 45 of its positions in the riser.

45 The deflector 31 and the handle 35 are supported from the transversely movable plate 36, the top portion of which is designed to conform with the contour of the riser cover 24. The sides 50

55

of the plate 36 are provided with the recesses 37 to permit the transverse movement of the plate. The lower end of the plate 36 is provided with the quadrant 38 for locking the deflector handle 5 35 in a predetermined position, the latter being provided with a suitable locking latch 39 to engage in the teeth of the quadrant. The portion 40 of the shaft 34 to which the handle 35 is attached is formed angularly to prevent movement of the deflector about its axis when the handle is in fixed position. The upper end of the shaft 34 is threaded as at 41 and a nut 42 holds the deflector in place.

The shaft 43 supported in the bearings 44 and 15 45 and having a threaded portion 46, extends transversely of the riser between the riser cover 24 and the plate 36. A threaded block 47 on the threaded portion 46 of the shaft 43 engages a slot 48 in the top portion of the plate 36. The 20 shaft 43 is operated by means of the hand wheel 49. Turning the hand wheel 49 revolves the screw 46 in the block 47, the block 47 as it moves along the screw 46 carries the plate 36 with it, which in turn moves the deflector 31. A few 25 turns in either direction will move the deflector to either the right or extreme left position. No appreciable effort is required to turn the hand wheel which can be readily adjusted during the time that the stoker is in operation or while the 30 stoker is at rest. The deflector responds to the slightest movement of the hand wheel giving the fireman the finest possible adjustment and maintains it at the desired point. Moving the plate 36 by means of the hand wheel does not in any 35 way interfere with the original setting of the deflector or deflector handle locking device.

If banks of fuel are formed on the left side, right side or center of the firebox, they can be burned away and the fire leveled out by so 40 adjusting the deflector as to starve the banked side and feed more coal to the opposite side, the same being true of the center. Thus if it is desired to starve the left side of the firebox, the hand wheel is turned to move the deflector nearer 45 the left side wall of the riser conduit and the deflector blade is adjusted at an angle to the left sidewall by moving the handle to the left side of the quadrant. The amount of fuel fed to the left side being determined by the proximity of the 50 rearward edge of the deflector vane to the left side wall of the riser. The closer the rearward edge of the deflector blade is to the riser left side wall the less fuel is fed to the left side of the firebox. Similarly banks may be removed from other parts of the firebox.

My new deflector permits of a wider range of 55 adjustments to positively insure a more even distribution resulting in a perfectly level fuel bed, higher firebox temperature, reduction in black smoke and instantaneously adjustable to quickly overcome banks in the firebed in any portion of the firebox.

It is apparent my new deflector has the advantage over types of deflectors now in use in 60 that the fireman can set the fluid pressure distributor jets at a suitable pressure permitting them to spread the coal uniformly and then compensate for any unevenness in the firebed by adjustment of the deflector without resorting to 65 changing the pressure of any of the jets. This greatly simplifies the duties of the fireman.

I claim:

1. In a stoker, a fuel conduit, a deflector in 70 said conduit for diverting fuel advanced therethrough, said deflector mounted on an approxi-

mately vertical pivotal axis movable in a horizontal direction transversely of the conduit, means operable for moving said deflector in a horizontal direction transversely of the conduit, and a second means operable for adjusting said deflector 5 angularly about its axis.

2. In a stoker, a fuel conduit, means associated with the conduit for diverting fuel advanced therethrough, said means arranged to be rotatable and movable in a horizontal direction transversely of said conduit, means for adjusting the degree of rotation of said fuel diverting means, and means for adjusting the horizontal transverse position of said fuel diverting means with respect to said conduit, said last 15 two named means being operated independently of each other.

3. In a stoker, a fuel conduit, a deflector in said conduit mounted on a pivotal axis movable transversely of the conduit, means operable for 20 moving said deflector in a straight line in a horizontal direction transversely of the conduit comprising a threaded shaft extending transversely of the conduit, a threaded block carried on said shaft, a plate engaged by said block arranged to 25 move transversely of the conduit by rotation of said threaded shaft, said deflector being carried by said movable plate, and means for adjusting said deflector angularly about its axis.

4. In a stoker, a fuel conduit, a deflector in said conduit mounted on a pivotal axis movable transversely of the conduit, means operable for moving said deflector in a straight line in a horizontal direction transversely of the conduit comprising a threaded shaft extending transversely of the conduit, a threaded block carried on said shaft, a plate engaged by said block arranged to move transversely of the conduit by rotation of said threaded shaft, said deflector being carried by said movable plate, and means for adjusting 30 said deflector angularly about its axis comprising a toothed quadrant on said movable plate, a handle having its one end secured to said deflector and its other end arranged to engage the 40 teeth of said quadrant and means for locking said handle in a predetermined position on said quadrant.

5. In a stoker, a feed conduit, a distributing means at the discharge end of said conduit, a fuel deflector pivotally mounted on an approximately vertical axis in said conduit in a position to act on the fuel being advanced therethrough before its delivery to said distributing means, means for varying the bodily position of 55 said deflector in a horizontal direction transversely of said conduit, and means for varying the angular position of said deflector about its axis.

6. In a stoker, a feed conduit, a distributing means at the discharge end of said conduit, a fuel deflector pivotally mounted on an approximately vertical axis in said conduit in a position to act on the fuel being advanced therethrough before its delivery to said distributing means, means for varying the bodily position of said deflector 60 in a horizontal direction transversely of said conduit, and means for varying the position of said deflector about its vertical axis independently of its bodily position.

7. In a fuel feeding conduit, a conduit section 70 extending upwardly and forwardly and terminating in a mouth portion, said section adjacent its mouth portion having therein a deflector vane pivotally mounted on an approximately vertical axis movable in a straight line in a horizontal 75

direction transversely of the conduit, means for so moving said axis, and means for adjusting said deflector vane angularly about its axis.

8. In a stoker, a fuel conduit, a fuel deflector vane associated with the conduit and being mounted to pivot about an axis, means for moving the position of said axis with respect to the conduit and independent thereof in a straight line in a horizontal direction to vary the bodily position of said vane, and means independent of the first named means for varying the angular position of the vane about said axis.

9. In a stoker, a fuel conduit, a fuel deflector vane associated with the conduit and being mounted to pivot about an approximately vertical axis, means for moving the position of said axis with respect to the conduit and independent thereof in a straight line in a horizontal direction to vary the bodily position of said vane, and means independent of said first named means for varying the angular position of the vane about its axis.
